METHOD AND MACHINE FOR GENERATING SPLINES AND THE LIKE

James L. Williamson, Springfield, Vt., assignor to
The Fellows Gear Shaper Company, Springfield,
Vt., a corporation of Vermont

Application February 18, 1944; Serial No. 522,852

11. Claims. (Cl. 90—7)

1.

The object of the present invention is to cut splines and similar formations with sharp angles at the roots of the splines by the molding generating process employing a planing cutter of the gear shaper type. The splines and similar formations here referred to usually have sides which, in planes perpendicular to the axis of the piece on which they are formed, are straight lines. Such formations, for the purposes of this specification, are called straight sided. However, the invention is not limited to the generation of straight sided splines, etc., exclusively, but may be applied in the production of formations with side faces which are otherwise than straight in the planes referred to. A further object is to cut such splines and the like in portions of shafts contiguous to a shoulder at one end, or shoulders at both ends, of the splines.

One of the problems solved by the invention is to produce splines in portions of shafts so close to shoulders thereon that the splines could not be formed there by milling cutters. Attempts have been made to generate splines in such locations by the well known molding generating process in which a cutter, having teeth on its circumference of conjugate outline to the outlines in cross section of the splines and intermediate spaces to be generated, is reciprocated endwise and lengthwise of the shaft while the cutter and shaft are rotated in harmonious ratio about their respective axes. But the cutters used in this fashion generally leave fillets at the intersections of the side faces of the splines with the root circumference of the shaft. A part of my present object is to avoid or obviate the formation of such fillets in the generation of splines and the like by the shaping procedure above mentioned, or an equivalent procedure. This phase of the object is accomplished by mounting the shaft or other work piece on a holder and rotating the holder about an axis at one side of, and at a considerable distance from, the axis of the work piece while the cutter is rotated about its own axis, the work piece being withheld from rotation by its own axis. This relative rotation may be carried on progressively and continuously, or intermittently, and is accompanied by a relative reciprocation between the work holder and the cutter lengthwise of the work piece, the cutter being so held that its axis of rotation extends in the same general direction as that of the relative reciprocation.

The invention consists in the method or procedure above outlined and in combinations of mechanical means by which such procedure may

2.

be performed automatically. An illustrative machine embodying such combinations, and the steps of the procedure are shown in the accompanying drawings and described in the following specification.

In the drawings:

Fig. 1 is a front elevation of the above mentioned illustrative machine, showing its principal parts;

10 Fig. 2 is a partial cross section taken on line 2—2 of Fig. 1, shown on an enlarged scale, and including a sectional view of indexing mechanism taken on line A—A of Figs. 1 and 8;

15 Figs. 3, 4 and 5 are fragmentary views illustrating three stages in the procedure of generating the adjacent sides of two splines and the groove between them;

20 Fig. 6 is a partial plan view showing a variation or reversal, from the arrangement shown in the preceding figures, of the relationship between the cutter and work pieces;

Fig. 7 is a vertical section of a portion of the work holder and work spindle of the machine taken on line 7—7 of Fig. 2;

25 Fig. 8 is a fragmentary sectional view taken on line 8—8 of Fig. 2;

Figs. 9 and 10 are detail sectional views taken on lines 9—9 and 10—10, respectively, of Fig. 7.

Like reference characters designate the same parts wherever they occur in all the figures.

Reference is made first to Figs. 2, 3, 4, 5 and 7 for illustration of the principles of the invention and the procedure by which the objects previously mentioned are realized. W represents a work piece, which may be a shaft, in which splines are to be generated in a portion or section W' between two shoulders S and S'; such shoulders, or one of them, being too near to the required location of the ends of the splines to permit cutting of the splines throughout their entire length by means of a milling cutter. A cutter C is provided for cutting the grooves between the splines and shaping the sides of the latter, such cutter being of the gear shaper type,

40 of disk formation, having teeth t on its circumference, of which the intersections between the sides and outer circumferential faces and one end face form cutting edges. Its teeth are short in the direction of the axis to enable them to commence cutting action at points near to an overhanging shoulder and are spaced apart sufficiently widely to insure that only one tooth will perform a cutting action on any work piece during any one generating traverse. The cutter is mounted on a suitable spindle, whereby it may

45

50

be rotated, with its axis D at one side of and parallel to the position occupied by the work piece when the cutting action is performed, and a relative reciprocation is effected between the cutter and work piece in the direction of the length of the work piece and of the axis of the cutter.

The work piece is mounted on a holder H, which is rotated, when in operation, about an axis E. The work piece is located at a distance greater than its own radius (preferably very much greater) from the axis E and is located relative to the cutter so that the portion of its circumference remote from the axis E is adapted to travel in an orbit (designated by the arc F), which intersects the circumference G of the cutter in which the outer extremities of the teeth *t* lie. The work piece is withheld from rotation about its own axis on the holder.

In the performance of the method, the holder H is progressively rotated about axis E and the cutter C rotated about its axis D at harmonious speeds such that the linear speed of the cutter teeth is equal to the linear speed of that portion of the work piece which travels in intersection with the circumferential line G. Such rotation is preferably continuous, but may be intermittent. In the course of this rotary movement of the cutter and work holder, a rapid relative reciprocating movement is effected between the cutter and work piece, whereby the cutter planes out a groove in the side of the work piece and generates the side and bottom surfaces of such groove.

It should be noted that the outlines of the cutter teeth are conjugate to the cross sectional contours of the sides of the splines to be generated and the bottoms of the intermediate grooves. Where the splines are required to have straight sides (that is, straight in planes perpendicular to the axis of the work piece), the side faces of the cutter teeth are curved with a conjugate curvature. The progress of cutting a groove between adjacent splines is indicated in Figs. 3, 4 and 5. The cutter is mounted in suitable angular relationship to its spindle and the work holder to cause one of its teeth *t* to reach the point of intersection between the circumferences G and F at the same time that the work piece in its travel reaches that intersection. With reference to Figs. 2-5, and assuming that the cutter and holder are rotated in the directions of the arrows applied thereto, the intersection point referred to is the point K, and the cutter is so disposed that the middle radius of one of its teeth and the common radius of the holder and work piece reach the point K at the same time. Cutting commences when the advancing side of the tooth encounters the work piece (these members being then substantially in the position shown in Fig. 3), and continues while the work piece and cutter tooth cross the line of centers D-E (the position shown in Fig. 4), and until they draw apart, as shown in Fig. 5. By virtue of the planetary movement of the work piece about an axis relatively remote from its own axis, the cutter generates clean, sharp angles between the sides *s* of the splines and the bottoms *b* of the grooves. That is, no fillets are left in these angles. And at the same time the desired contours of the splines extend all the way to the outside circumference of the work piece; that is, they are not rounded off at the outer extremities.

Preferably the invention includes, further,

mounting a large number of work pieces in a circular series around the work holder axis E, rotating the holder so as to carry the work pieces, one after the other, past the cutter and cause a groove to be cut in each, indexing each work piece after a groove has been cut in it, and continuing to circulate the work pieces through their orbit past the cutter, and index them, one or more times, until a prescribed desired number of splines have been cut. Where provision is made for thus actuating a series of work pieces, the spacing of the work pieces and the spacing of the teeth of the cutter are so correlated with one another and their relative speeds of rotation that, as each work piece approaches and crosses the line of centers D-E, a cutter tooth also approaches and crosses the line of centers in the manner and with the generative effect precedent-ly described. It is immaterial what the diameter and number of teeth of the cutter are, provided only that they, and the speed of rotation, are such as to produce that effect, and that the cutter teeth are suitably spaced apart to avoid simultaneous cutting of two grooves in any work piece at a greater or less distance apart than the prescribed width of a spline.

The work holder H is a turret secured to a shaft 12 which, as shown by broken lines in Fig. 1, is rotatably mounted in the base of a suitable machine frame 13. The turret has a rim 14 carrying aligned spaced apart centers 15 and 16 between which the work piece is held. The centers 15 are mounted in a flange 17 surrounding and integral with the rim 14, while the centers 16 are individually carried by separate spring retracted slides 18, one of which is shown in Fig. 7. The slide 18 as here shown is a bar fitted in a socket which enters the rim 14 from the top thereof. A spring 19 surrounds the inner end portion of the slide and is confined between a head 20 on the extremity of the slide and a ring 21 which bears against a shoulder 22 in the walls of the socket. The slide protrudes from the upper extremity of rim 14 and to its outer end is secured a block 23 extending outwardly from the rim and in the overhanging portion of which the center 16 is secured. An arm 24 projects from the outer end of slide 18 oppositely to the block 23 and carries an adjustable stop screw 25 arranged to bear on the upper face of rim 14 for limiting the movement of the slide 18 inwardly and of the center 16 toward the center 15. The slide may be raised to disengage center 16 from the work piece when the work is to be changed. For insuring correct alinement of the center 16 with 15, a key 26 is secured to the slide and is adapted to enter a notch or keyway 27 in the rim.

The work piece is prevented from rotating on the centers by a retractable bolt 28 fitted to slide radially in the rim 14 and having a tapered nose or key portion 29 on its extremity which is pressed outward by a spring 30 into a notch formed in the work piece, or in an index disk secured to the work piece, adjacent to the shoulder S' or elsewhere. There are as many such notches in this part of the work piece or the index disk as the number of splines to be cut in the part W'; and the bolt is adapted to enter any one of such notches. The bolt is retracted, to permit indexing of the work, by automatic means later described in connection with the indexing means.

The cutter C is secured to a spindle 31 mounted to rotate and reciprocate in a saddle 32 which

is supported by guideways 33 on a beam 34 mounted on the base 13. The spindle is reciprocated by mechanism substantially like that shown in the patent to E. R. Fellows 1,662,109, March 13, 1928; and the cutter spindle and turret shaft 12 are rotated by worm and wheel gearing and transmission mechanism, shown in a general way by broken lines in Fig. 1. In respect to the correlated driving means for the cutter spindle and turret shaft, this machine is similar to one of the standard models of Fellows gear shaping machines, wherefore no description in detail thereof is needed herein. It is sufficient for the purposes of this disclosure that suitable means are provided for producing correlated rotation of the cutter and work holding turret and for reciprocating the cutter lengthwise of its axis and of the work pieces, or otherwise effecting an equivalent reciprocative relative movement between the cutter and work.

Indexing means is provided for turning the work pieces about their own axes through the prescribed angle between the centers of adjacent splines. Such indexing means includes a pawl 35 connected by a pivot 36 with a bracket 37 which rises from a stationary part of the machine base beside the turret or work holder H. The extremity of the pawl 35 projects from the bracket 37 toward the work holder far enough to enter one of the notches 38 in the notched or toothed part of the work piece, or attached index disk, which is engaged by the bolt 28. A spring 39 is connected with an anchor pin 40 on the bracket 37 and with a pin 41 on the pawl and is so located that it constantly exerts force tending to hold the pawl 35 against a stop pin 42, and normally holding it in that position. But progress of a work piece after striking the end of the pawl displaces the latter from the stop pin.

The bolt 28 is disengaged from the work piece or index disk to permit indexing of the latter by the following means. A rod 43 is slidably mounted in the lower part of the turret rim 14 and has a conical end 44 protruding into the entrance of a chamber 45 in the under side of bolt 28 and engaging the inclined bounding wall 46 of the chamber. A spring 47 surrounds the rod 43 and is held under compression between a shoulder 48 on the rod and an internal shoulder 49 in the turret, normally holding the shoulder 48 against a ring 491 secured in the entrance opening of the passage which contains the rod. In its normal position the extremity of the rod enters chamber 45 only a short distance and is close to the inclined wall 46. Hence when the rod is moved upward, it enters chamber 45 more deeply and exerts a wedging force on the wall 46, withdrawing the bolt from the work pieces. A wedge block 50 (Fig. 10) is secured to the stationary machine base beneath the overhanging turret H and at the same distance from the axis of the turret as the rods 43 of the several work supporting devices of the turn table. A part of the wedge block rises above the path in which the protruding lower extremities of the rods 43 travel, and has an inclined surface 51 crossing such path and arranged to be engaged by and to lift rod 43 when the latter is carried past it.

The block 50 is located in relation to the pawl 35 so as to raise the rod 43, thereby withdrawing the bolt 28 from the work piece, and release the bolt while the pawl 35 is in one of the notches 38 of the indexing portion of the work piece and bearing against the trailing side of that notch. During so much of the travel of the turret as

occurs before the bolt is fully withdrawn, the pawl is displaced with the work piece; and as soon as the bolt releases the piece, spring 39 returns the pawl to its stop 42 and so rotates the work piece about the axis of centers 15 and 16. Further travel of the turret while the pawl stands still completes indexing rotation of the work. The dwell period during which the bolt is held back after being retracted is determined by the width of the top face 52 of the wedge block and of the bottom face 53 of pin 43; and these faces may be made as wide or narrow as needed to time the release of bolt 28 with the arrival of the following notch 38 of the work piece in registering position.

The indexing means thus described may be located in any desired point around the circumference of the turret, it being necessary only that indexing be completed before the indexed work piece comes into operating relation with the cutter.

It will be apparent from the foregoing description that splines or other formations of the desired character are cut successively in a number of work pieces, and progressively in each work piece, until the prescribed number of splines have been cut in all the pieces, automatically.

In the operating relationship before described the cutter is located outside of the rim of the work holder or turret. This is not an essential arrangement; but the work grasping centers may be reversed with respect to the turret rim and the cutter located between the orbit in which the work pieces revolve and the axis of the orbit. This reversed arrangement is shown illustratively in Fig. 6. The operation in the reversed arrangement is essentially the same as before described, with the exception that the rate of rotation of the cutter is in ratio with the rate of travel of the inner boundaries of the work pieces instead of that of their outermost boundaries.

What I claim and desire to secure by Letters Patent is:

1. The method of generating splines and the like in shafts without formation of fillets at the roots of the splines or undesired rounding of their outer extremities, which comprise effecting relative cutting traverse between a work piece and a cutting tool, having a tooth with a cutting edge conjugate to the contour to be generated in the work piece, revolving the work piece about an axis at one side of its own axis and causing any given element of the work piece to remain in fixed angular relation to a line between the work piece and the axis of revolution while the work piece passes the cutter, and simultaneously rotating the cutter so that the said tooth is revolved in an orbit which is transverse to the directions of such reciprocation and intersects the orbit in which a portion of the work piece is revolved about the before mentioned axis.

2. The method of generating splines and analogous formations in shafts without producing undesired curves in the side faces of such splines, which comprises revolving the shaft in which such formation is to be generated about an axis at one side of its own axis, and causing it to be withheld from rotation about its own axis, rotating a planing cutter which is provided on its circumference with a tooth of outline conjugate to the formation to be generated, about an axis so positioned that the tooth is enabled to incise the side of the shaft, correlating the rate of revolution of the shaft and rotation of the cutter so that the linear

velocity of the cutter tooth is equal to the linear velocity of the side of the shaft next to the cutter, and effecting a relative planing action between the cutter and shaft lengthwise of the shaft.

3. The method of generating splines in shafts without undesired curvatures, which comprises revolving a shaft in an orbit around an axis substantially parallel to its own axis, while causing a given diameter of the shaft to remain in the same radial relationship to such orbit while passing the cutter, mounting a circular gear shaper cutter at one side of such orbit in a position such that a tooth of the cutter may incise the shaft, rotating the cutter in time with the revolution of the shaft with a pitch line velocity equal to the velocity in its orbit of the side of the shaft nearer to the cutter, and reciprocating the cutter lengthwise of the shaft in the course of such relative rotation and revolution.

4. The method of generating splines and similar formations in shafts and the like, which comprises revolving such a shaft in an orbit around an axis substantially parallel to the length dimension of the shaft and causing a given diameter of the shaft to be and remain in fixed radial relation to such axis while passing in cutting relation with the after mentioned cutting tool, providing a cutting tool having a lateral tooth with cutting edges in an outline conjugate to the contour designed to be generated in the spaces between adjacent splines, rotating said tool about an axis substantially parallel to that of the orbit in which the shaft revolves so that the tooth revolves in an orbit which intersects the path of that side of the shaft which is nearest to the rotational axis of the cutter when passing the cutter, causing the linear speed of revolution of the tooth and the said nearest side of the shaft to be equal, locating the cutter with respect to its axis so that the tooth and the said nearest side of the shaft cross the line of centers between the axis of revolution of the cutter tooth and the axis of revolution of the shaft together, and reciprocating the cutter lengthwise of the shaft while crossing said line of centers.

5. In the generation of splined shafts by the gear shaping procedure with relative reciprocation between a shaping cutter and a shaft lengthwise of the latter, the new steps which comprise causing the shaft to revolve in an orbit around an axis spaced apart from its own axis while causing the same side of the shaft to face toward its axis of revolution during passage of the shaft in cutting relation with the cutter, and simultaneously rotating the cutter at a speed in generative cutting harmony with the speed at which the side of the shaft nearest to the cutter travels in its orbit.

6. A splined shaft generating machine comprising a rotatably mounted turret having a plurality of shaft holders arranged to carry a circular series of shafts with their axes parallel to the axis of the turret and with one side of all the shafts tangent to a circumference centered on the turret axis and including means for locking the shaft so that it cannot rotate relatively to the turret, a cutter spindle mounted with its axis parallel to the turret axis and arranged to hold a gear shaper cutter with the circumference in which the teeth thereof are located substantially tangent to the before named circumference, means for rotating the spindle and turret at harmonious speeds such that the linear travel of the cutter teeth is substantially equal to the linear travel of the sides of the shafts which pass near-

est to the spindle, and means for reciprocating the spindle endwise to cause planing action by means of the cutter teeth upon the shafts as the latter successively approach, cross and recede from the line of centers of the turret and spindle.

7. A splined shaft generating machine comprising a rotatably mounted turret, means on the turret for holding shafts in a circular arrangement around the axis of the turret and with their length dimension substantially parallel to that axis, a cutter spindle adapted to carry a planing cutter of gear shaper type, releasable means on the turret for preventing rotation of the several shafts, means for reciprocating the spindle, means for rotating the turret and spindle simultaneously at correlated angular velocities, and means for successively releasing the several shafts and imparting to them, when released, an increment of angular movement about their own shafts at a point in their orbit where they are clear of engagement with the cutter.

8. A splined shaft generating machine comprising a rotatable carrier, means thereon adapted to hold a shaft at one side of the axis of the carrier with its length substantially parallel to said axis, a releasable dog engaging the shaft to prevent rotation thereof about its own axis, a gear shaper cutter mounted rotatably and reciprocatively adjacent to the path in which the shaft is carried by rotation of the carrier, means for reciprocating the cutter and for rotating the cutter and carrier in correlation to cause generative cutting by the cutter of spline faces in the shaft, and means for releasing said dog, turning the shaft about its own axis, and reengaging the dog with the shaft at a point in the orbit of the shaft where the shaft is clear of the cutter.

9. In a machine of the character described, a rotatably mounted turret, work holding centers mounted on the turret at one side of the axis of rotation thereof, spaced apart in a line extending lengthwise of said axis, a bolt mounted on the turret having an extremity projecting toward the line between said work holding centers, a spring acting on the bolt tending to force it outward, a rod mounted in the turret extending parallel to the line of said centers having an inclined surface engaged with an inclined surface of the bolt, and a stationary wedge block mounted in position to engage said rod during the rotation of the turret and move the same endwise, the rod when so moved acting to displace the bolt against the pressure of its spring.

10. The combination with the turret and other parts set forth in claim 9, of a pawl mounted in a stationary location adjacent to the exterior of the turret in position to engage a work piece held between said centers when the bolt is displaced in the manner set forth.

11. A machine for generating splines and similar formations in shafts and the like, comprising a rotatable holder, means carried by said holder for mounting a work piece thereon at a distance from, and with that portion in which a spline is to be formed in a position substantially parallel to the axis of rotation of the holder and including means for locking the shaft so that it cannot rotate relatively to the holder, a rotatable cutter spindle mounted adjacent to the orbit in which the work piece is revolved by said holder, a planing cutter mounted on said spindle having a tooth projecting laterally from the spindle axis with cutting edges at one end in an outline conjugate to the adjacent sides of, and the surface between, two splines to be generated, said tooth being lo-

cated to rotate in an orbit which intersects the orbit in which the outer side of the work piece revolves when the holder is rotated, means for simultaneously rotating the work holder and cutter spindle at angular speeds and in directions so related that the outer extremity of the cutter tooth and a point within the outer side of the work piece travel at the same linear speed and in the same direction when crossing the line of centers of the work holder and spindle, and means for reciprocating the cutter spindle endwise during the traverse of the cutter tooth and work piece between the points at which their respective orbits intersect.
